(57) **CLAIM**

The ornamental design for an adjustable trailer hitch, as shown and described.

DESCRIPTION

FIG. 1 is a front, left, top perspective view of the first embodiment of an adjustable trailer hitch, showing my new design;

FIG. 2 is a rear, right, bottom perspective view thereof;
FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 2;

FIG. 13 is an enlarged view of detail 13 in FIG. 5;

FIG. 14 is an enlarged view of detail 14 in FIG. 5;

FIG. 15 is an enlarged view of detail 15 in FIG. 7;

FIG. 16 is an enlarged view of detail 16 in FIG. 7;

FIG. 17 is a front, left, top perspective view of the second embodiment of an adjustable trailer hitch, showing my new design;

FIG. 18 is a rear, right, bottom perspective view thereof;
FIG. 19 is a front elevational view of the enlarged scale thereof;

FIG. 20 is a rear elevational view of the enlarged scale thereof;

FIG. 21 is a left side view of the enlarged scale thereof;

FIG. 22 is a right side view of the enlarged scale thereof;

FIG. 23 is a top plan view of the enlarged scale thereof;

FIG. 24 is a bottom plan view of the enlarged scale thereof;

FIG. 25 is an enlarged view of detail 25 in FIG. 17;

FIG. 26 is an enlarged view of detail 26 in FIG. 17;

FIG. 27 is an enlarged view of detail 27 in FIG. 17;

FIG. 28 is an enlarged view of detail 28 in FIG. 18;

FIG. 29 is an enlarged view of detail 29 in FIG. 18;

FIG. 30 is an enlarged view of detail 30 in FIG. 22;

FIG. 31 is an enlarged view of detail 31 in FIG. 22;

FIG. 32 is an enlarged view of detail 32 in FIG. 23; and,

FIG. 33 is an enlarged view of detail 33 in FIG. 23.

The dashed broken lines in the figures are for the purposes of illustrating portions of the adjustable trailer hitch and form no part of the claimed design.

The short-short-long dashed broken lines immediately adjacent to the claimed areas in the views represent the boundaries of the design and form no part of the claimed design.

(Continued)

The dash-dot-dash broken lines are for notating enlarged views and form no part of the claimed design.

1 Claim, 33 Drawing Sheets
